Primary Examiner — Austin Murphy(74) *Attorney, Agent, or Firm* — Cantor Colburn LLP**CLAIM**

The ornamental design for the brush head, as shown and described.

DESCRIPTION

FIG. 1 is a perspective view of a brush head according to the present disclosure;

FIG. 2 is a first side view of the brush head of FIG. 1;
FIG. 3 is a second, opposite side view of the brush head of FIG. 1;

FIG. 4 is a front view of the brush head of FIG. 1;
FIG. 5 is a rear view of the brush head of FIG. 1;
FIG. 6 is a top view of the brush head of FIG. 1; and,
FIG. 7 is a bottom view of the brush head of FIG. 1.
The broken lines in the drawings illustrating environmental
structure or boundaries that form no part of the claimed
design.

1 Claim, 5 Drawing Sheets# US D851,412 S
